ILLUMINATED FILLING NOZZLE

Harlan C. Todd and Paul R. Todd, Martin, S. Dak.

Application March 19, 1935, Serial No. 11,847

5 Claims. (Cl. 240—2)

This invention relates to illuminating filling nozzles.

One of the objects of the invention is to devise a fitting for attachment to a valve controlled nozzle for dispensing gasoline in which is mounted a source of illumination so that the interior of the gasoline tanks being filled may be seen by the operator.

Another feature of the present invention is to devise a thoroughly insulated mounting in the device so as to eliminate any possibility of fire from short circuits or sparks in the device.

Further objects of the invention are to provide a device of the character referred to that is strong, compact and durable, thoroughly reliable for its intended purpose, designed particularly for attachment to outlet nozzles, that is easily assembled and disassembled from the nozzle, and comparatively inexpensive to manufacture.

With the foregoing and other objects in view the invention consists of a novel construction, combination and arrangement of parts as will be hereinafter more specifically described and illustrated in the accompanying drawings wherein is disclosed an embodiment of the invention, but it is to be understood that changes, variations, and modifications may be resorted to without departing from the spirit of the claims hereunto appended.

In the drawings wherein like reference characters denote corresponding parts throughout the several views:

Figure 1 is a side elevation of a valve controlled filling nozzle illustrating an adaptation thereof with of a device in accordance with the present invention.

Figure 2 is an enlarged fragmentary sectional view of the attachment.

Figure 3 is a radial section through one branch of the attachment taken substantially on line 3—3 of Figure 1 and looking in the direction of the arrows.

Figure 4 is a side elevation of the light support removed from the one branch.

Figure 5 is a perspective view of the reflecting sleeve.

Referring to the drawings in detail, 7 indicates the outlet conductor of a filling nozzle A of the conventional character used in dispensing gasoline. The filling nozzle includes a valve 8 operating in response to the stem 9 which stem is controlled by the lever 10 rockably on a pin 11 and this pin is mounted in a hand guard 12 carried by the nozzle A. The rear end of the nozzle A 13 is customarily connected with a flexible pipe 13

which conveys the gasoline being dispensed from the pump. The nozzle A is customarily inserted in the neck on the gasoline storage tank of the automobile and by pressing the lever 10 the gasoline is dispensed therethrough.

The fitting of the present invention is indicated generally at B and this fitting is substantially Y-shaped and includes the stem 14 and the two branches 15 and 16. The branch 16 is on the same axis as the stem 14 so that the source of illumination, to be presently described, will reflect light out through the open end of the stem 14 through which the gasoline passes. The rear end of the stem merges with the branch 15 and the inner end of this branch 15 is formed with an interiorly threaded flange 17 that is detachably secured to the free end of the nozzle A. The branch 16 merges with stem 14 slightly above the juncture of the branch passage 15a and the stem passage 14a, so that the source of illumination may be mounted and confined solely in the branch 16 so as not to interfere with the passage of the gasoline from passage 15a and out through stem passage 14a. The gasoline from the nozzle A passes through branch 15 into the stem 14 and out through the open end of the stem. The branch 15 and the branch 16 are disposed at an angle with respect to each other.

Where the branch 15 joins or merges with the stem 14 there is an outset shoulder 18 on the branch 16 which forms a ledge on the interior of branch 16 on which rests the rubber strip 19. The interior of branch 16 forms the light chamber 16a above the shoulder. There is a lens 20 supported on the rubber strip 19 which lens is plane on the outer face and convex on the inner face. In the light chamber mounted co-axial therewith is a light reflecting sleeve 21, the inner end of which rests upon the margin of the plane face of the lens 20.

Resting on the other end of the sleeve 21 is a fibre insulating disk 22 having a marginal flange 23 conformably fitting the end of the reflector. In the center of the disk 22 is supported a light socket 24 in which is detachably connected the light bulb 25. So as to insure perfect insulation there is mounted a knob 26 of sealing wax about the outer end of the plug and through the sealing wax knob 26 extends the electrical conductor wires 27, 28. To hold the electric light supporting disk 22 there is a bowl shaped cap 29 threadably connected with the end of the branch 16 as at 30. In the crown of the cap 29 there is mounted in an opening therein, the

screw bushing 31 formed with a central opening through which the electrical conductor wires extend. The inner face of the disk support 22 reflects the light and the sleeve 21 also reflects light directly down through the stem 14 so that light will be thrown into the gasoline tank for the convenience of the operator.

We propose to use a low voltage in the device and for this purpose we use an ordinary flashlight bulb 25. To insure the utmost safety we install in the electrical conductor wires 27, 28 a safety fuse that will disrupt the current in event of any short circuit. The electrical conductor wires 27, 28 lead to a transformer (not shown) which transformer may be connected with the lighting circuit of a filling station (not shown). By coupling the light bulb 25 with a low voltage circuit, utmost safety is insured so that no short circuit or sparks are likely to cause fire when dispensing the gasoline.

Having thus described the invention, what is claimed as new is:

1. The combination with a valve controlled filling nozzle of a Y-shaped pipe fitting including a stem and two branches, one of said branches being disposed on the same axis as the stem, the end of the other branch being adapted for attaching to the filling nozzle, and an electric light mounted and confined solely in the other branch for directing light into the stem.

2. A valve controlled filling nozzle including a conductor having the discharge end equipped for detachable connection to another conductor; the combination with the aforesaid elements of a Y-shaped tubular fitting including a stem and two branches, an outset shoulder formed about the juncture of one branch with the stem and on the interior thereof, the assembly of elements constituting a source of illumination receiving their support at one end from said shoulder, a cap detachably connected with the free end of said one branch cooperating with the aforesaid as-

sembly of elements to retain said assembly confined solely within said branch in supported relation on said shoulder, and means on the free end of the other branch for detachable connection to the nozzle conductor.

3. In combination, a filling nozzle for inflammable fluids equipped with an attaching means on the discharge end, a substantially Y-shaped fitting including hollow branches and a hollow stem, one branch provided with a fitting on its free end adapted for detachable connection with the aforesaid attaching means, said one branch and stem forming an outlet passage for the inflammable fluid, and a source of illumination mounted and sealed within the other branch above the juncture of the stem and said one branch in a manner to reflect light through the free end of the stem.

4. In combination with a dispensing nozzle for inflammable fluids of a fitting detachably connected at one end with the nozzle and formed with a passage through which inflammable liquids are discharged from the nozzle, said fitting having a hollow branch joined thereto and communicating with the passage in a direction diverging therefrom, and a source of illumination mounted in and confined in the branch above the juncture in a manner to reflect light through the free end of the fitting.

5. In combination with a dispensing nozzle for inflammable fluids having a hollow passage for discharging fluid of a hollow branch joined with the nozzle and communicating with the discharge passage, said branch disposed in a direction diverging from the path of flow through the nozzle, and a source of illumination mounted and confined in the branch above the juncture in a manner to reflect light through the free end of the nozzle.
